UNITED STATES PATENT OFFICE.

JACOB KNOTT, OF PATERSON, NEW JERSEY.

FIBER-COVERED METALLIC TUBING, A DEVICE FOR SILK STRETCHING AND DRYING.
MACHINES.

1,088,029.

Specification of Letters Patent. Patented Feb. 24, 1914.

Application filed March 20, 1913. Serial No. 755,723.

To all whom it may concern:

Be it known that I, JACOB KNOTT, a citizen of the United States, residing at 230 Clinton street, in the city of Paterson, in 5 the county of Passaic and State of New Jersey, have invented certain new and useful Improvements in Fiber-Covered Metallic Tubing, a Device for Silk Stretching and Drying Machines, of which the following is 10 a specification, reference being had therein to the accompanying drawing.

My invention relates to improvements in means for hanging or suspending skeins of silk in an apparatus for stretching and drying silk, such as the apparatus shown in my U. S. Letters-Patent No. 969,960, patented September 13, 1910. In drying and stretching machines of that character, it has been the custom to use sticks or metal bars 20 or tubing, which pass through the skeins, to all of which there are objections; namely, sticks are not strong enough for the strain, and the silk is apt to catch on all of said skein holding means as the metal ones are 25 apt to get wet and rust.

The objects of my improvement are, first, to provide for hanging or suspending the silk-skeins a means which will be strong, light and durable, that will have a hard, 30 smooth surface not apt to catch or engage and entangle in any way with the silk thread; second, to produce a means, for hanging or suspending silk in machines of the character above stated, that may be extended and shortened to meet the demands or requirements of the number of skeins of silk that are to be stretched and dried; third, to produce in a machine for stretching and drying skeins of silk, a means for hanging 35 and suspending the silk, consisting of a vulcanized fiber-covered metallic tubing; and fourth, to provide sleeves of vulcanized fiber, telescopic tubes in said sleeves for supporting skeins of silk passed around said sleeves, 40 and means within said tubes for operating and guiding the inner tube and to prevent it from turning. I attain these objects by the mechanism illustrated in the accompanying drawings, in which—

50 Figure 1 is a section of metal tubing partly covered by the fiber covering or sleeve; Fig. 2 an end view of the same; Fig. 3 is an illustration in longitudinal section

of the telescopic sections of adjustable fiber-covered metallic tubes and means for operating the same; Fig. 4 is an end view looking at the operating end of device; Fig. 5 is an end view showing the telescoping portions and guide rods looking at the other end, and Fig. 6 is a crank or key for turning the threaded rod to operate the telescopic sections to lengthen or shorten the same.

Similar letters refer to similar parts throughout the several views.

The fiber sleeve or covering F is vulcanized, hard, dense, closely resembling horn in texture, and has a very smooth surface and is made of vegetable fiber. The silk therefore cannot catch or be entangled by the smooth surface of the fiber sleeve or covering and both the metal tube and its fiber covering contributes to the strength of my device, which may be called a skein-holding device for silk drying and stretching machines.

The tubing M is covered by the sleeve of fiber F and is meant to take the place of the rods described in my above mentioned patent and the skeins of silk are hung around 80 my fiber-covered tubing in a chain or series in the same manner as described in said patent.

Sometimes it happens that there are more skeins of silk to be stretched and dried than 85 can be accommodated around the rods or fiber-covered tubing on one machine, but are nevertheless not enough to fill the rods or fiber-covered tubing of another machine, hence, I provide two fiber-covered tubes 90 adapted to telescope or pass one within the other and which may be operated by the handle —f— to extend or withdraw the inner tube from or into the outer tubing, which tubes are shown in longitudinal section in Fig. 3. To prevent the inner tube from turning, I provide guide rods —e— which are secured in the fixed nut —c— and which pass through the collar —d— in the inner tube. The fixed nut —c— in the outer 100 tube is interiorly threaded and the operating screw —a— passes through said nut, and according to the direction in which said screw —a— is turned, it forces the inner tube out from or draws it into the outer 105 tube. As shown in Fig. 3 the screw bolt

—*b*— passes loosely through the fixed collar —*d*— in the inner tube and is screwed into the inner end of the screw —*a*—. The fixed nut —*c*— in the outer tube and the fixed collar in the inner tube, and the guide rods —*e*— secured in the nut —*c*— and passing slidably through the fixed collar —*d*— in the inner tube, comprise a reinforcement or strengthening element to the telescopic portions of the inner and outer tubes.

My tubes are preferably constructed of metal and while the invention has been described with particular reference to the 15 tails of construction, it is not to be considered as limited thereto, as many changes may be made without departing from the scope of the following claims.

What I claim:—

- 20 1. A skein-holding device for silk drying and stretching machines, comprising a vulcanized fiber-covered tubing.
2. A skein-holding device for silk drying and stretching machines, comprising in combination a metallic tube and a covering for the same, consisting of a sleeve of vulcanized vegetable fiber.
- 25 3. A skein-holding device for silk drying and stretching machines, comprising in com-

bination telescopic sections of vulcanized 30 fiber-covered tubing.

4. A skein-holding device for silk drying and stretching machines, comprising in combination telescopic sections of vulcanized 35 fiber-covered tubing and means within said tubes for operating said telescopic sections, to adjust the length of the skein-holder.

5. A skein holding device for silk drying and stretching machines, comprising in combination telescopic sections of vulcanized 40 fiber-covered tubing, means within said tubes for operating and guiding the inner tube and to prevent it from turning in adjusting the length of the skein-holder.

6. In a skein-holder for silk drying and 45 stretching machines, a tube of any suitable substance, provided with a sleeve or covering of vegetable fiber, vulcanized to produce a hard, dense surface, closely resembling horn in texture and presenting a very 50 smooth surface, substantially as set forth.

In testimony whereof I affix my signature in presence of two witnesses.

JACOB KNOTT.
